UNITED STATES PATENT OFFICE

2,034,278

LAMINATED METAL STOCK

Frederick M. Becket, New York, and Russell Franks, Jackson Heights, N. Y., assignors to Electro Metallurgical Company, a corporation of West Virginia

Application April 19, 1934, Serial No. 721,308

6 Claims. (Cl. 29—181)

The invention relates to composite, laminated steel sheets, plates, tubes and the like; and refers more specifically to new and improved laminated sheets, plates, tubes and similar articles comprising a body of ordinary corrodible iron or steel provided with a surface portion or facing of corrosion resistant chromium alloy steel.

Considerable effort has been expended in attempts to produce articles of this type, in order to obtain a relatively inexpensive material that is resistant to corrosion, and meritorious commercial products have been developed. However, certain difficulties have been encountered in the fabrication and use of the known types of laminated articles, most of which difficulties are directly attributable to the marked tendency of ferritic chromium steels containing about 2% to about 16% chromium to harden when rapidly cooled, air-cooled for example, from the elevated temperatures ordinarily required in rolling the material. The air-hardening characteristics of these chromium steels are so marked that during hot-working they must be handled rapidly, lest they cool rapidly to too low a temperature, harden, and crack. In order to soften them, they must be annealed for several hours at the proper temperature and subsequently cooled very slowly from the annealing temperature almost to a black heat.

Although ferritic steels containing about 16% to 30% chromium do not air-harden to anything like the extent to which the 2% to 16% chromium steels do and are not very hard inherently, they lack ductility and toughness in the hot-rolled state, and long annealing periods are required to impart satisfactory ductility.

On the other hand, the ordinary carbon steels used as a backing or body material for these composite articles are readily softened within a relatively few minutes when they are heated under the proper conditions, and they do not exhibit air-hardening tendencies. Laminated articles fabricated from ordinary carbon steel on one side and ferritic chromium steel on the other show marked differences in hardness on the two sides, because even after annealing the plain carbon steel is softer than the steel containing chromium. In some instances, this is a result of the fact that long annealing periods cannot be employed for fully softening the chromium steel side, because in so doing the plain carbon steel side would be badly oxidized. If the annealing is done in an inert or reducing atmosphere, this difficulty may be partially eliminated; but such special treat-

ment is by no means a complete solution of the problem.

One result of the difference in hardness of the two sides of the laminated products heretofore known is that during rolling to the desired thickness the two materials are reduced by different amounts, which in some instances is a disadvantage.

Further difficulties result from the radically different manner in which volumetric changes take place in the chromium and carbon steels, respectively, upon heating and cooling. These effects may on occasion adversely affect the bond between the two materials, and there is a tendency for thin sheets of the laminated materials to curl.

It is an object of the invention to obviate the above and other difficulties in the fabrication and use of laminated articles comprising alternate laminae of chromium alloy steel and ordinary carbon steel.

According to the invention, laminated articles are provided by affixing to a base or body of iron or carbon steel a facing or surface layer of chromium alloy steel which is substantially less hardenable than those heretofore used for the purpose.

Suitable chromium steels include those described in our joint applications Serial Number 640,778, filed November 2, 1932, Serial Number 640,900 filed November 2, 1932, (now Patent 30,1954,344) and Serial Number 694,057, filed October 24, 1933.

One steel described in our said prior applications comprises about 2% to 30% chromium; carbon in amounts up to 0.50%, but preferably not over 0.2% in the steels containing about 2% to about 16% chromium and not over 0.3% in the steels containing about 16% to 30% chromium; and titanium, the titanium content being at least about twice the carbon content, and being not more than about four times the carbon content plus 1% (preferably 0.5%) of the total alloy; the balance being chiefly iron.

Another steel described in the said applications comprises iron, chromium, carbon, and columbium, the ranges of chromium and carbon being the same as in the case of the above-identified iron-chromium-carbon-titanium steels, and the columbium content being at least about four times the carbon content and being not greater than eight times the carbon content plus about 2% (preferably 1%) of the total alloy, the balance being chiefly iron.

A third steel described in our said applications comprises iron, chromium, carbon, and vanadi-

um, in substantially the proportions: 3.5% to 20% chromium; carbon in amounts not over about 0.1%; and at least about five times the carbon content but not over 1% of vanadium; 5 the remainder chiefly iron.

The laminated article of the invention may be fabricated by cleaning a surface of a sheet, plate, or tube of iron or structural grade steel, clean-

numbers of the mild steel being given as a range of a large number of determinations made on several representative sheets. The hardness numbers of the chromium steel sides are averages of several numbers obtained at several points on the surface of each sheet. The Erichsen numbers were obtained on laminated sheets about 0.035 inch thick. 5

10

15

20

25

ing a surface of a suitable piece of non-hardenable chromium alloy steel, fastening the two steels together with the cleaned surfaces in juxtaposition, and welding the said surfaces by hot-rolling or forging in known manner. If desired, a thin sheet of soft iron, copper, nickel, or other soft metal, or a soft alloy, may be interposed between the said surfaces to aid in forming a secure bond; but such an expedient will not ordinarily be necessary.

Another method of making the article of the invention is to cast the corrodible base metal against a surface of a sheet of non-hardenable chromium alloy steel, and subsequently to hot-roll or to forge the composite article.

In the accompanying drawing, the sole figure 45 is a cross-sectional view of a typical article embodying the invention, showing a sheet of iron or mild steel united to a sheet of non-hardenable chromium steel.

The chromium alloy steel of decreased hardenability forming the surface portion of the laminated article of the invention exhibits in the as-rolled state a surface hardness and thermal properties approaching those of iron and ordinary steel much more closely than do the air-hardenable 2% to 16% chromium steel and the 16% to 30% chromium steel heretofore used for the purpose. Moreover, the non-hardenable alloy steel may be fully softened by an annealing treatment which consists simply in heating the steel at a temperature in the neighborhood of 800° to 900° C. for a few minutes, five minutes to one-half hour for example.

Comparative tests have been made of laminated sheets comprising single sheets of mild steel (0.07% carbon) united to single sheets of chromium steel free from titanium, columbium, and vanadium, and to single sheets of non-hardenable chromium steels, respectively. The following table includes representative data from these 70 tests. Analyses are given in each case of the metal on the chromium steel side, and the mild steel side, respectively, the balance of the metal being substantially all iron. The Rockwell "B" hardness numbers were taken on each side of 75 laminated sheets 0.09 inch thick, the hardness

tends to decrease the effect of the carbon, said additional metal being at least one of the group consisting of columbium, titanium, and vanadium; the remainder principally iron; all of said 5 laminæ having similar hardness, ductility, and expansion characteristics during heating and cooling, and undergoing similar reductions in thickness when hot worked.

2. Laminated articles which may be hot or cold 10 worked in the same manner as a solid mild steel article and consisting of at least one lamina composed of mild steel and at least one lamina composed of a substantially non-hardenable steel containing about 2% to 30% chromium; carbon 15 in amounts up to about 0.3%; and titanium, the titanium content being at least about twice the carbon content but not more than about four times the carbon content plus 1%; the balance principally iron; all of said laminæ having similar hardness, ductility, and expansion characteristics during heating and cooling, and undergoing similar reductions in thickness when hot worked.

3. Laminated articles which may be hot or cold worked in the same manner as a solid mild 20 steel article and consisting of at least one lamina composed of mild steel and at least one lamina composed of a substantially non-hardenable steel containing about 2% to 16% chromium; carbon 25 in amounts up to about 0.2%; and titanium, the titanium content being at least about four times the carbon content but not more than about four times the carbon content plus 0.5%; the balance principally iron; all of said laminæ having similar hardness, ductility, and expansion characteristics during heating and cooling, and undergoing similar reductions in thickness when hot worked.

4. Laminated articles which may be hot or cold worked in the same manner as a solid mild 30 steel article and consisting of at least one lamina composed of mild steel and at least one lamina composed of a substantially non-hardenable steel 35

containing about 2% to 30% chromium; carbon in amounts up to about 0.3%; and columbium, the columbium content being at least about four times the carbon content and being not greater than about eight times the carbon content plus 5 about 2%; the balance principally iron; all of said laminæ having similar hardness, ductility, and expansion characteristics during heating and cooling, and undergoing similar reductions in 10 thickness when hot worked.

5. Laminated articles which may be hot or cold worked in the same manner as a solid mild steel article and consisting of at least one lamina composed of mild steel and at least one lamina composed of a substantially non-hardenable steel 15 containing about 2% to 16% chromium; carbon in amounts up to about 0.2%; and columbium, the columbium content being at least about eight times the carbon content and being not greater than eight times the carbon content plus about 20 1%; the balance principally iron; all of said laminæ having similar hardness, ductility, and expansion characteristics during heating and cooling, and undergoing similar reductions in 25 thickness when hot worked.

6. Laminated articles which may be hot or cold worked in the same manner as a solid mild steel article and consisting of at least one lamina composed of mild steel and at least one lamina composed of a substantially non-hardenable steel 30 containing about 3.5% to 20% chromium; carbon in amounts up to about 0.1%; and at least about five times the carbon content but not over 1% vanadium; the remainder chiefly iron; all of said laminæ having similar hardness, ductility, and 35 expansion characteristics during heating and cooling, and undergoing similar reductions in thickness when hot worked.
